SNOWPLOW

James Atchison Begley, Maniwaki, Quebec,
Canada

Application August 13, 1940, Serial No. 352,439

6 Claims. (Cl. 37—42)

This invention relates to snow plows, adapted to be connected to the front of a vehicle for forward propulsion and particularly to an improved carriage frame and supplemental supporting frame for snow plows.

The primary object of this invention is to provide a light yet durable carriage frame, that will allow the plow mould board to rise at either end portion independently of the opposite end portion when encountering an obstruction on the road surface.

In contemplating the above objective, I have provided a carriage frame with pivotally mounted thrust bars which rest independently on spring members to provide a resilient, bi-motional attachment to the supporting frame. It follows, the thrust bars are also pivotally attached to the said supporting frame. Thus, for example, when the left end of the mould board encounters an obstruction on the road bed, it will rise substantially vertically and the left thrust bar will settle on the supporting spring member without altering the position of the right thrust bar and right end of the mould board to any appreciable extent.

A further object of the invention conditional to the primary object is to provide means whereby the mould board may meet, and be elevated over, an obstruction on the road bed with a minimum amount of shock to the mould board, carriage frame and supporting frame.

A still further object of the invention is to provide a carriage frame of extremely simple construction giving due regard to strength and efficiency.

Still another important object of the invention is to provide a supplemental supporting frame that may be easily attached to the vehicle chassis in a manner whereby the weight of the said supporting frame and carriage frame is supported above the vehicle springs to alleviate stress and strain on the wheels and axles of the vehicle. I have accomplished this object by securing the supporting frame to the longitudinal members of the vehicle chassis in a manner so that certain brace supports are bolted or otherwise secured over the front wheels.

A still further object is to provide adjustable thrust bar facilities so that the mould board may be yieldably maintained at varying determined positions relative to the road bed.

With these and other objects in view which may appear as the description proceeds the invention resides in the novel construction and arrangement of co-operating parts as hereinafter more specifically set forth, claimed and shown in

the accompanying drawings forming part of this application and in which:

Fig. 1 is a plan view of the improved carriage frame, showing its position relative to the vehicle chassis and mould board.

Fig. 2 is a rear end elevation view of the carriage frame.

Fig. 3 is a side elevation view of the device in which the carriage frame and supplemental supporting frame are disclosed.

Fig. 4 is a perspective view of the supplemental supporting frame.

Referring more in detail to the drawings in which similar reference characters designate corresponding parts throughout the several views, I have shown a vehicle chassis 10 to which the supplemental supporting frame is secured. It may be noted here that, although a particular vehicle chassis has been taken for purpose of illustration, the device may be readily secured to any standard vehicle in a similar manner with due consideration being given to structural modification of a minor nature.

The supplemental supporting frame consists of two upright supports 11 and 12 which are connected to each other by upper and lower lateral and parallel braces 13 and 14 which are welded or otherwise secured to the upright supports. I have provided channels 15 and 16 to receive the thrust bars of the carriage frame which will hereinafter be described in detail. The said channels, depend from and are partially supported by the lower lateral brace 14. Aligned holes 17 are provided in the channels so that the thrust bars may be adjustably secured to the supplemental supporting frame. A lateral brace 18 is secured to the lower extremities of the said channel members 15 and 16. In the drawings Figure 4, I have shown the combination of angle iron and strap iron for a channel member, but it should be understood that two lengths of angle iron or one length of channel iron of predetermined size would suffice. The present combination is to provide means of adjusting the width of the channels 15 and 16.

The support frame is connected to the chassis 10 by means of inclined braces 19 and 20, welded or otherwise secured to the lateral brace 18 and extending rearwardly to the chassis 10 and bolted thereto above the wheels 21 of the vehicle. The said inclined brace members are supplemented by coacting braces 22 and 23 secured to the lateral support 14 at either extremity and extending rearwardly to the chassis frame 10 where they are secured in any suitable manner. A strap

iron connecting member 24 may be provided to strengthen and relate the braces whereby the supplementary supporting member is attached to the chassis.

Angle plates, generally designated as 25 are suitably disposed throughout the structure at the various positions where torque is likely to occur to alleviate this strain.

It will be seen, particularly in Fig. 3, that the usual attachments are provided as a necessary part of the equipment but are not claimed as being new and useful in the art such as the headlights 26 and plow hoisting mechanism 27. It will be readily noticed I have used angle iron bracing throughout the construction of the supplemental supporting frame, however, it should be understood that the method of attaching the said supporting frame is the primary feature which is claimed and various modifications of a minor nature may be resorted to in the actual construction.

The carriage frame A which forms, in part, the subject matter of this application is attached to the mould board 28 by means of the pivotally mounted links 29 which extend from the angle bar 30 which is in turn supported on the carriage frame A by the inclined brace members generally designated as 31. The carriage frame is provided with a pair of supporting shoes 32 arranged in spaced apart relation to each other immediately adjacent the angle bar 30. These shoes 32 are adapted to support the mould board a predetermined distance above the ground level and to relieve the wear and tear on the mould board.

The upper portion of the mould board 28 is supported substantially centrally by an adjustable brace rod 33 which is composed of telescopic members pivotally attached to the mould board by lugs 34 and to the carriage frame A in the same manner 35. A plurality of holes 36 are provided in the tubular portion of the brace rod 33 whereby the length of the said rod may be varied to position the mould board at the proper angle with respect to the road surface.

The immediately preceding paragraphs have described a simple and efficient mould board and mould board attachment means that I have successfully adapted for the purpose of the invention, in combination with the carriage frame to be hereinafter described in detail. However, my carriage frame is such that it may be used on any type of mould board attachment with slight modification and in addition is equally successful used in combination with the one-way type of mould board and the V-type of mould board. Therefore, it should be understood that the carriage frame is a distinct unit adaptable to be successfully used with the majority of snow plow mould boards.

In carrying out the objects associated with the carriage frame, I have provided a rectangular lower frame 37 made of angle iron to which two thrust bars 38 and 39 are pivotally anchored at the forward end of the frame by means of the bolt 40 and anchor rod 41. Each of the thrust bars extend rearwardly between the outer vertical guide bars 42 and the inner vertical guide bars 43 which extend from the rearward end of the lower frame 37. A cross member 44 is welded to the said guide bars at the upper extremity to rigidly retain same in position. The carriage frame is attached to the supplemental supporting frame by means of the thrust bars 38 and 39 which are hingedly connected to the supporting

frame by means of pivot bolts 45 through the channels 15 and 16.

Reverting to the thrust bars 38 and 39 it will be seen particularly in Fig. 2, that they rest upon and are supported in the raised position by spring leaves 46 on which metal spaces 47 are situated to alleviate the wear and tear on the spring leaves. The said spring leaves are bolted at 48 to the lower frame 37 and are maintained in guides at their extremities between the vertical guide bars 42 and spaced apart guide bars 49 which extend vertically from the base 37.

In summing up the particular advantages of the structure it will be noted that the supplemental frame may be readily attached to and detached from the chassis by means of bolts through the said chassis and the braces 19, 20, and 22, 23. During the period when a more or less permanent use of the device is required the supplemental supporting frame is left on the vehicle chassis and the mould board and carriage frame quickly and easily detached to the said supporting frame by simply removing the pivot bolts 45 from the channels 15 and 16 and allowing the thrust bars 38 and 39 to be removed from the said channels.

In operation the mould board is held in a road engaging position by the inclination of the thrust bars 38 and 39 in combination with the adjustable brace rod 33; however, the resilient spring supports 46 allow for vertical elevation of the mould board 28 as a whole, or at either extremity without materially effecting the position of the opposite extremity.

It is believed that the advantages of the structure shown will be apparent from the foregoing paragraphs taken in conjunction with the accompanying drawings without further detailed description.

While the preferred embodiment of the invention has been disclosed it is understood that minor changes in the details of construction and arrangement of co-operating parts may be resorted to within the scope of what is claimed without departing from the spirit of the invention.

I claim:

1. An improvement in snow plows, comprising in combination with a supplemental supporting frame and snow plow mould board, a carriage frame to which the mould board is attached, thrust bars resiliently mounted on the carriage frame adapted to be pivotally secured to the supplementary supporting frame so that the mould board may be automatically elevated upon encountering an obstruction.

2. A device as claimed in claim 1, wherein the thrust bars are resiliently mounted independently of each other to support each end of the mould board in separately yielding engagement.

3. An improvement in snow plows, comprising in combination with a supplemental supporting frame and snow plow mould board a carriage frame adjustably secured to the said supplemental supporting frame, by thrust bars pivotally anchored to the said carriage frame and yieldingly supported by resilient members thereon.

4. An improvement in snow plows, comprising, in combination with a snow plow mould board, mould board supporting shoes and means to adjust the angle of inclination of the said mould board and a supplementary supporting frame, a carriage frame attached to the mould board and thrust bars pivotally attached to the carriage

frame and supported independently of each other by spring members, the said thrust bars being adjustable and pivotally attached to the supplementary supporting frame by pivot bolts through channels in the said supporting frame.

5. A device as claimed in claim 4, in which the supplementary supporting frame is secured to the chassis by means of brace members which extend rearwardly of the vertical braces and the lateral channel brace.

6. An improvement in snow plows, a carriage

frame having brace structures extending therefrom to support a snow plow mould board, thrust bars pivotally anchored to the carriage frame and yieldingly supported independently of each other by spring leaves bolted to the said carriage frame, guide channels to control the lateral movement of the said thrust bars and guide channels to control the lateral movement of the spring leaves and means to limit the upward movement of the said thrust bars.

JAMES ATCHESON BEGLEY.
